CLAIM

I claim the ornamental design for a portfolio, as shown and described.

DESCRIPTION

FIG. 1 is a perspective view of my new portfolio design;

FIG. 2 is a top plan view thereof;

FIG. 3 is a bottom plan view thereof;

FIG. 4 is a rear elevational view thereof;

FIG. 5 is a front elevational view thereof;

FIG. 6 is a right-hand side elevational view thereof; and,

FIG. 7 is a left-hand side elevational view thereof.

The dashed lines shown in FIGS. 1, 2, 3 and 7 represent stitching. These dashed lines form part of the claimed design.
